HYDRAULIC PUMP

Charles H. Rystrom, Rockford, Ill.

Application October 4, 1945, Serial No. 620,346

3 Claims. (Cl. 103—162)

1

My invention relates generally to hydraulic pumps, and more particularly to hydraulic pumps of the swash plate type, which may also be used as hydraulic motors.

In pumps of the swash plate type, the pistons or plungers are carried by a rotating barrel which is pressed against a head, and, as the barrel rotates, the pistons at one side of the barrel are discharging the hydraulic fluid under pressure, while the pistons on the other side of the barrel are executing a suction stroke. The forces acting on the barrel, tending to move it away from the valve seat surface, are therefore greater on one side than on the other, which tends to cause the cylinder barrel to tilt. Such tilting tendency of the barrel places strains on the barrel supporting shaft and may cause leakage at the seal between the barrel and valve surface of the head.

It is the primary object of the invention to provide a pump or motor of the swash plate type, in which the forces acting upon the pump barrel are substantially balanced, so that the cylinder barrel presses uniformly against the valve surface formed on the head of the pump.

A further object is to provide an improved pump or motor of the swash plate type having a plurality of concentric rows of pistons and cylinders, with an improved head construction whereby the pistons of the two rows may be operated in opposite phase, that is, while the outer row of pistons on one side of a diametral line are executing a discharge stroke, the adjacent pistons are executing a suction stroke, and vice versa, so that at all times the forces tending to press the cylinder barrel against the head plate will be substantially balanced.

A further object is to provide an improved head construction including outlet and inlet passageways, whereby a plurality of concentric rows of pistons and cylinders may be employed in a pump or motor of the swash plate type.

Other objects will appear from the following description, reference being had to the accompanying drawings, in which:

Fig. 1 is a central longitudinal sectional view of the improved pump and motor; and

Fig. 2 is a sectional view thereof, taken on the line 2—2 of Fig. 1.

Referring to Fig. 1, the pump or motor comprises a body casing 10 having heads 12 and 13 secured thereto as by tie bolts (not shown). A shaft 14 is mounted for rotation in an anti-friction thrust bearing 16, secured in the head plate 12, and in an anti-friction bearing 18 suitably

2

mounted in the head 13. An oil seal 20 is held in place by a gland 22 secured to the head 12. A cylinder barrel 24 is keyed to the shaft 14 and is pressed against the head 13 by a spring 26 compressed between a washer 28 and the barrel 24.

The contacting valve surfaces of the head 13 and barrel 24 are suitably finished so as to provide an oil tight seal. The barrel is provided with a suitable number of outer cylinders 30 and a similar row of inner cylinders 32. Pistons or plungers 34 are reciprocable in the outer cylinders, while plungers 36 are reciprocable in the inner row of cylinders.

Each of the plungers 34 and 36 is provided with a head 38 which is recessed to receive a hardened steel ball 40 and is retracted from its cylinder by a coil spring 42 compressed between the barrel 24 and the head 38. The balls 40 of the outer row of plungers 36 have flat surfaces slidably engaging a thrust ring 44 mounted in an anti-friction bearing 46, having thrust rollers 47 and radial rollers 48. The anti-friction bearing 46 is mounted on an annular block 50 which is suitably secured to the head 12. It will be noted that the surface of the block 50 upon which the anti-friction bearing 46 rests is at an angle with respect to the axis of the shaft 14.

In a similar manner, the plungers 36 of the inner row are in engagement with a thrust plate 52 mounted on an anti-friction bearing 54 carried by an annular mounting block 56. The blocks 50 and 56 are suitably secured to the head 12 as by cap screws extending through the head 12 and into the blocks or in any other suitable manner. It will be noted that the surface of the block 56 upon which the anti-friction bearing 54 rests is inclined with reference to the axis of the shaft 14 in a direction opposite to that in which the corresponding surface of the block 50 is inclined. The block 56 is provided with a bearing bushing 57 for the shaft 14.

The head 13 has an outlet passageway 60 and an inlet passageway 62 formed therein. As best shown in Fig. 2, the passageway 62 has an arcuate portion 62a in alignment with the outer row of cylinders 30 and a portion 62b in alignment with the inner row of cylinders 32, the portions 62a and 62b being joined by a portion 62c. In a similar manner, the passageway 60 has an outer portion 60a which is in alignment with the outer cylinders 30, and a portion 60b in alignment with the inner row of cylinders 32, the portions 60a and 60b being joined by a connecting portion 60c.

The cylinders 38 have ports 68 which, as the barrel 24 rotates, are in alignment with a substantially semi-circular port 68 during substantially one-half a revolution, and with a substantially semi-circular arcuate port 69 during the remainder of the revolution. It will be noted that the port 68 is in communication with the passageway 62 while the port 69 is in communication with passageway 60. In a similar manner, ports 70 of the cylinders 32 of the inner row are in registry with ports 72 and ports 73 each during substantially one-half a revolution. The port 72 communicates with the portion 60b of the passageway 60, while the port 73 communicates with the portion 62b of the passageway 62.

Assuming that the shaft 14 is driven in the direction of the arrow marked thereon in Fig. 1, that is, counterclockwise as viewed in Fig. 2, it will be seen that the plunger 36 which is directly above the shaft 14 is commencing movement into its cylinder 32, discharging the oil therefrom through the port 72 and passageway 60 from which the lubricant may flow through an outlet conduit 74 which is suitably connected to a cover plate 16 attached by cap screws 78 to the head 13. On the other hand, the piston 36 positioned directly beneath the shaft 14 is commencing retractive movement under the influence of its compressed spring 42, and therefore drawing oil from the portion 62b of passageway 62. Oil is supplied to the passageway 62 through a conduit 80 which is suitably connected to a cover plate 82 secured to the head 13 by cap screws 84.

On the other hand, the outer piston 34 above the shaft 14 is commencing its suction stroke, while the piston 34 directly below the shaft 14 is commencing its discharge stroke. The remaining plungers are in intermediate positions. Thus the forces applied to the cylinder barrel 24 by all of the plungers or pistons 34, 36, tend to balance so that there is but a relatively small net force tending to cause the cylinder barrel to tilt in a manner such that it does not contact the head 13 throughout the contacting surface thereof.

It is clear that the forces acting upon the cylinder barrel 24, due to the compressive strokes of the outer row of plungers 34, have a greater torque effect tending to tilt the cylinder barrel 24 than do the forces due to the compressive strokes of the inner row of plungers 36, and thus a complete torque balance is not effected by the construction shown, in which the plungers 34 and 36 are of the same diameter, and of the same number. However, for practical manufacturing and servicing reasons, it is desirable to have the plungers 34 and 36 interchangeable, and the cylinders 30 and 32 of the same diameter. If desired, the number of plungers 34, or the effective areas thereof, may be reduced by about one-third in order to cause the torques applied to the cylinder barrel due to the compressive strokes of the plungers 34, to balance the torques due to the compressive strokes of the plungers 36. Such reduction of one-third in the number or effective areas of plungers 34 would accomplish such torque balance if the plungers 34 are 1.5 times as far from the axis of the shaft 14 as the plungers 36. Such complete balancing of the torques, either by decreasing the number of plungers in the outer row, or by decreasing the diameters thereof, is contemplated in pumps or motors in which long service-free life and precision operation are important requirements. However, for ordinary use, the pump may be constructed with equal numbers of plungers 34 and 36, and with

these plungers of equal diameters and strokes, since the economies of manufacture will ordinarily be of more importance than obtaining exact torque balance on the cylinder barrel 24.

While the apparatus has been described primarily as a pump, it will be clear that by applying a hydraulic fluid under pressure to the apparatus through the conduit 80, rotation of the cylinder barrel 24 and shaft 14 may be effected, provided free discharge of the hydraulic fluid from the conduit 74 is permitted. When used either as a pump or as a motor, the load or torque on the shaft 14 is more uniform due to the substantial equalization of the forces applied to or by the plungers. This is of particular advantage when the apparatus is used as a motor to drive a machine or part at constant uniform speed. Due to the use of a plurality of concentric rows of pistons and cylinders, the apparatus of small overall dimensions will have large displacement when used as a pump, and conversely, when used as a motor, is capable of delivering greater power than conventional types of fluid motors of equal overall dimensions. Thus in the claims, wherein the invention is generally defined as a pump, it will be understood that a similar structure used as a motor is intended to be included.

While I have shown and described a preferred embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

40 I claim:

1. In a pump of the swash plate type, the combination of a housing, a head at one end of the housing, said head having four arcuate ports each extending throughout substantially a semi-circle and at two different radial distances from the center of the head, said head being provided with two passageways each in communication with an inner port and a diametrically opposite outer port, a cylinder barrel having a pair of 45 concentric rows of cylinders having ports respectively registerable with the inner and outer arcuate ports, a plunger in each of the cylinders, means to cause rotation of said cylinder barrel, and two swash plates engaged by the plungers to cause reciprocation of each of said plungers once 50 during each revolution of the cylinder barrel, the swash plates being oppositely inclined with respect to the axis of the barrel thereby to cause the reciprocation of the plungers of the inner and outer rows to take place in opposite phase.

2. A pump of the swash plate type having a rotatable cylinder barrel having two concentric rows of cylinders therein, a spring retracted plunger in each of said cylinders, means to rotate the cylinder barrel, and a stationary swash plate engaging the ends of the plungers in each row, the swash plates being inclined in opposite directions with respect to the axis of the cylinder barrel.

3. In a pump of the swash plate type, a housing, a cylinder barrel rotatable within said housing and bearing against one end thereof, a shaft for rotating said barrel, said barrel having a plurality of concentric rows of cylinders formed 70 therein, the end of the housing against which the

barrel bears being provided with valve ports with which the ends of the cylinders are registrable, plungers respectively reciprocable in said cylinders, and means for reciprocating the plungers of the two rows in opposite phases, whereby the plungers of one row on one side of a diametral plane through the barrel are executing discharge strokes while the plungers of the other row are executing suction strokes, the end of said housing against which the barrel bears being provided with two passageways, one connecting all the ports which are in registry with cylinders in which the plungers are executing discharge strokes, and the other passageway connecting all ports which are in registry with cylinders in which the plungers are executing suction strokes.
